(57) **CLAIM**

The ornamental design for a braided spring pop-up toy with round head, as shown and described.

DESCRIPTION

FIG. 1 is a top perspective view of a braided spring pop-up toy with round head;

FIG. 2 is a bottom perspective view thereof;

FIG. 3 is a front view thereof, the rear view being the same,
FIG. 4 is a right side view thereof, the left side view being the
same;

FIG. 5 is a top view thereof; and,

FIG. 6 is a bottom view thereof, the broken lines are for
environmental purposes only and form no part of the claimed
design.
